UNITED STATES PATENT OFFICE

2,480,685

BANK DEPOSITORY

William E. Adams, Hamilton, Ohio, assignor to
 Herring-Hall-Marvin Safe Company, Hamilton,
 Ohio, a corporation of New York

Application March 1, 1946, Serial No. 651,157

12 Claims. (Cl. 232—44)

1

The present invention relates to bank depositories of the type enabling depositors safely to make deposits after banking hours, and which are commonly known as night depositories. More particularly, the invention relates to the deposit receiving, outside entrance to such depositories.

For the convenience of depositors who are unable to make deposits during regular banking hours, many banks provide a supplementary safe or vault within the bank which connects with an outside entrance by means of a chute. At the entrance to the chute a lockable deposit receptacle is provided which is movable from a charging position in which the deposit is placed (usually contained in a leather envelope) to a discharging position in which the entrance is closed and the deposit is dropped through the chute into the vault. Normally, the receptacle is locked in the discharging position by a key-operated lock actuated by means of the depositor's key. Often, however, and particularly when a deposit is of such size as to fit tightly in the receptacle, it fails to drop into the chute. Since, when the receptacle is in a discharging position the entrance is closed, the depositor has no assurance that his deposit has safely entered the chute and the vault and he may relock the entrance with the deposit still in the receptacle.

It is, therefore, one of the principal objects of this invention to provide a deposit receiving and discharging device for the entrance to a night depository which will prevent carelessness on the part of the depositor in ascertaining whether his deposit has safely been discharged therefrom.

Another object of the invention is to provide a device of the above character which incorporates means in the deposit receptacle which are responsive to the weight or pressure of the deposit therein to prevent relocking the depository entrance until the deposit has been discharged or removed therefrom.

Still another object of this invention is to provide a device of the above character which is adapted to be relocked in a closed position and incorporating means preventing removal of the key from the lock while a deposit is in the entrance receptacle.

With these and other objects in view, the invention consists in the parts and combinations hereinafter set forth with the understanding that various changes may be made therein, such as the size, shape and arrangement of parts and in the substituting equivalents, by those skilled in the art, without departing from the spirit of 55

2

the invention or exceeding the scope of the appended claims.

In order to make the invention more clearly understood a preferred embodiment thereof has been made the subject of illustration in the accompany drawings in which:

Figure 1 is a front elevational view of a night depository entrance with parts broken away to better illustrate features of the invention.

10 Figure 2 is a cross sectional view taken along the line 2—2 of Figure 1 looking in the direction of the arrows, the depository entrance being shown in an open or deposit-receiving position.

15 Figure 3 is a cross sectional view taken along the line 3—3 of Figure 1 looking in the direction of the arrows, the depository entrance being shown in a closed or deposit-discharging position.

20 Figure 4 is a fragmental sectional view taken along the line 4—4 of Figure 3 showing the associated parts of the locking bolt and bolt-blocking mechanism in an unlocked position.

25 Figure 5 is a fragmental sectional view taken along the line 5—5 of Figure 4 looking in the direction of the arrows.

Figure 6 is a view in perspective of the lock bolt-blocking element.

Generally, the invention comprises a cylinder having a transverse passageway therethrough 30 and rotatably mounted within a casing which is embedded in the wall of a bank building. The cylinder is adapted to be rotated about its axis from a deposit-receiving position, where the passageway therein communicates with an entrance

35 opening in the casing, to a deposit-discharging position where the said passage is moved out of communication with the entrance opening, to close the same, and into communication with an exit opening in the casing which connects with

40 a downwardly directed chute leading to a safe conveniently located in the bank building below the level of the depository entrance. The cylinder is adapted to be locked in the latter position by a key actuated sliding bolt carried by the casing

45 and adapted to be received in a socket in the cylinder. The lock is of the type from which the key may not be withdrawn except when the bolt is in locked position.

A deposit responsive device, preferably in the form of a spring loaded swingable plate forms the floor of the deposit passage in the cylinder and has an operative connection with a blocking element which is moved thereby, when a deposit is inserted in the passageway, to a position into the path of the locking bolt to prevent the bolt

entering its socket in the cylinder. Thus, it will be seen that when the cylinder is rotated to a discharging position where it may be locked, the lock may not be actuated to relock the depository entrance and the key removed unless the deposit is discharged from the passageway.

Describing the specific embodiment of the invention in more detail, a casing 1 having a cylindrical wall 2 and end walls 3 is embedded in the outside wall 4 of the bank building. One side of the casing wall 2 is preferably flattened and lies flush with the face of the wall 4 and has provided therein an entrance opening 5. The wall 2 is also provided with an exit opening 6 which is angularly disposed with respect to the opening 5 and connects with the upper end of a chute 7. The lower end of the chute 7 is adapted to connect with a vault or other suitable receptacle (not shown) conveniently located within in the bank building.

Preferably, a face plate 8 is secured to the face of the bank wall 4 and is provided with an opening 9 which registers with the opening 5 and the casing 1. Adapted to cover the openings 9 and 5 is a door 10 which is hinged at its lower edge to the face plate 8 and is provided with a flanged recess 11 forming a hand hold for opening and closing the door. Positioned above the door 10 is a hood 12 behind which may be placed, if desired, a light, not shown.

Within the casing 1 is a cylinder 13 comprising a cylindrical wall 14 to which are attached circular end walls 15. Each end wall 15 is provided with a trunnion 16 respectively journaled in sockets 17 in the end walls 3 of the casing 1 to mount the cylinder 13 for rotation therein. The cylinder 13 is provided with a pair of spaced parallel transverse walls 18 and 19 which with the end walls 15, define a passageway 20 extending substantially diametrically through the cylinder. To rotate the cylinder by opening and closing movement of the door 10, a link 21 has a pivotal connection 22 at one of its ends with the door 10 and a pivotal connection 23 at its opposite end with one of the end plates 15 of the cylinder. Preferably, the link 21 is mounted for movement in an angular depression 24 in the outer face of the end plate 15, the sides of the depression 24 serving by engagement with the link 21, to limit the movement of the cylinder 13 so that when the door 10 is open and the cylinder is in a deposit-receiving position as shown in Figure 2, the entrance end of the passage 20 will register with the entrance opening 5, and when the door 10 is closed and the cylinder is in discharging position, as shown in Figure 3, the opposite end of the passageway will register with the discharge opening 6 of the casing. It will also be noted from Figures 2 and 3 that the construction of the cylinder 13 and the arrangement of the entrance and discharge openings of the casing 1 are such that when the cylinder 13 is in position to receive a deposit, the exit opening 6 is blocked, and when the cylinder 13 is rotated to the deposit discharged position, the entrance opening 5 is blocked.

In order to lock the cylinder 13 in its closed or discharging position, one of the end walls 15 is provided with a socket 26 for the reception of a bolt 27, slidably carried in a lock-housing 28. The socket 26 is positioned to align axially, in the discharging position of the cylinder 13, with an aperture 29 in the adjacent side wall 3 of the casing through which the bolt passes. The bolt 27 is arranged to be actuated by an arm 30

carried by the end of a spindle 31 which extends rearwardly from the tumbler barrel 32 of a key-actuated lock 34 of the well known type from which the key may not be removed unless the bolt is in its extended or locking position. Preferably a detent arrangement, such as indicated generally by the spring-loaded ball 35 and cooperating spaced annular grooves 36 in the bolt 27, is provided to restrain movement of the bolt in either its locked or unlocked position.

Mounted within the passageway 20 is a plate 37 which has a hinged connection 38 at its forward edge with the cylinder 13 adjacent the forward edge of the passageway. This plate 37 is substantially coextensive in length and width with the passageway and forms, in effect, a movable wall thereof. Attached to the plate 37 adjacent one edge thereof at a point removed from hinge 38 is one end of a shouldered pin 39 which passes through a counter bored hole 40 in the wall 19. The opposite end of the pin 39 has a limited universal connection with one end of a bell crank arm 41 which is pivoted by means of a post 41' to the inner face of one of the end walls 15 of the cylinder 13. The crank arm 41 is provided with a right-angular extension 42 which terminates in a block 43. The extension 42 passes through an aperture 44 in the wall 15 which connects with the socket 26. A compression spring 30 45 is positioned between the shoulder of the pin 39 and the shoulder of the counter bored hole 40 and serves normally to urge the plate 37 in a direction outwardly from the bottom of the passageway 20 and the crank arm 41 in the direction to move the block 43 thereon away from the socket 26. When, however, a deposit is placed in the passage 20, its weight or pressure, if the package is of a size sufficient to wedge into the passageway, overcomes the force of the spring 45 and moves the plate 37 and the arm 41 in the opposite direction to move the block 43 into the socket 26. As seen in Figure 4, the length of the extension 42 is such that the outer face of the block 43 lies substantially flush with the outer face of the cylinder end plate so that when the arm 41 is in the latter described position the entrance to the socket is blocked.

The operation of the device, if is believed, will be apparent from the foregoing. The operation 50 may be summarized, however, as follows: The depositor first unlocks the depository entrance by inserting his key and retracting the bolt 27 from the socket 26. This releases the cylinder 13 and the door 10 may then be opened which rotates the cylinder, through action of the lever 21, to its deposit-receiving position shown in Figure 2. The deposit is then placed in the passageway 20 which depresses the plate 37 rocking the bell crank about its pivot to move the block 43 into the socket 26, thereby blocking movement of the bolt 65 into the socket. The door 10 is then closed by the depositor returning the cylinder to the discharging position such as shown in Figure 3. If the deposit is sufficiently small, it will slide by gravity through the exit opening 6 and into the chute 7 down to the depository, the entrance relocked and the key withdrawn. If, however, the deposit remains lodged in the passage, its pressure 70 sure or weight maintains the plate in its depressed condition and the blocking element in the socket 26 in which condition the lock may not be actuated to relock the cylinder and depositor cannot withdraw his key from the lock. This gives the depositor a clear indication that his deposit still

remains in the cylinder and he may reopen the depository entrance and adjust the package or remove some of his contents so that the deposit may freely move from the passage in its discharging position into the chute and depository.

I claim:

1. In a depository of the class described, a casing having an entrance and an exit opening, a cylinder rotatably mounted in the casing, said cylinder having a deposit receptacle therein adapted to register successively with the entrance and exit openings upon rotation of the cylinder from a deposit receiving to a deposit discharging position, means operative for locking the cylinder in a discharging position, and means including a movable plate member constituting side wall of the receptacle and extending substantially the full depth thereof, said means being actuated by pressure of a deposit on the plate in all positions of the deposit in said receptacle for rendering the locking means inoperative.

2. In a depository of the class described, a casing having an entrance and an exit opening, a cylinder rotatably mounted in the casing, said cylinder having a deposit receptacle therein adapted to register successively with the entrance and exit openings upon rotation of the cylinder from a deposit receiving to a deposit discharging position, locking means including a bolt movable in the casing to engage the cylinder and lock the same in a discharging position, a blocking member movable to an operative position to prevent engagement of said bolt with said cylinder, and means actuated by a deposit in said receptacle for moving the blocking member to said operative position.

3. In a depository of the class described, a casing having an entrance and an exit opening, a cylinder rotatably mounted in the casing, said cylinder having a deposit receptacle therein adapted to register successively with the entrance and exit openings upon rotation of the cylinder from a deposit receiving to a deposit discharging position, locking means including a bolt movable in the casing to engage the cylinder and lock the same in a discharging position, a blocking member movable to an operative position to prevent engagement of said bolt with said cylinder, and means including a movable plate member in said receptacle and having a positive connection with the blocking member, said plate member being moved by pressure of a deposit thereon for moving the blocking member to said operative position.

4. In a depository of the class described, a casing having an entrance and an exit opening, a cylinder rotatably mounted in the casing, said cylinder having a deposit receptacle therein adapted to register successively with the entrance and exit openings upon rotation of the cylinder from a deposit receiving to a deposit discharging position, locking means including a bolt movable in the casing to engage the cylinder and lock the same in a discharging position, a blocking member movable to an operative position to prevent engagement of said bolt with said cylinder, spring means normally urging the blocking member to an inoperative position, and means opposed to said spring means and actuated by a deposit in said receptacle for moving the blocking member to said operative position.

5. In a depository of the class described, a casing having an entrance and an exit opening, a cylinder rotatably mounted in the casing, said cyl-

inder having a deposit receptacle therein adapted to register successively with the entrance and exit openings upon rotation of the cylinder from a deposit receiving to a deposit discharging position, locking means including a bolt slideable in the casing, said cylinder having a socket positioned to receive the bolt when the cylinder is in a discharging position, a blocking member carried by the cylinder and movable to block and unblock the entrance to said socket, means operative for locking the cylinder in a discharging position, and means actuated by a deposit in said receptacle for moving the blocking member to block said socket entrance.

10 6. In a depository of the class described, a casing having an entrance and an exit opening, a cylinder rotatably mounted in the casing, said cylinder having a deposit receptacle therein adapted to register successively with the entrance and exit openings upon rotation of the cylinder from a deposit receiving to a deposit discharging position, locking means including a bolt slideable in the casing, said cylinder having a socket positioned to receive the bolt when the cylinder is in a discharging position, a blocking member carried by the cylinder and movable to block and unblock the entrance to said socket, and means including a movable plate member in said receptacle and having a positive connection with said blocking member, said plate being moved by pressure thereon of a deposit for moving the blocking member to block said socket.

20 7. In a depository of the class described, a casing having an entrance and an exit opening, a cylinder rotatably mounted in the casing, said cylinder having a deposit receptacle therein adapted to register successively with the entrance and exit openings upon rotation of the cylinder from a deposit receiving to a deposit discharging position, locking means including a bolt slideable in the casing, said cylinder having a socket positioned to receive the bolt when the cylinder is in a discharging position, a blocking member carried by the cylinder and movable to block and unblock the entrance to said socket, and means including a movable plate member in said receptacle and having a positive connection with said blocking member, said plate being moved by pressure thereon of a deposit for moving the blocking member to block said socket, and resilient means normally urging said blocking member in a direction to unblock said socket.

25 8. In a depository of the class described, a substantially cylindrical casing having an entrance opening in the cylindrical wall thereof and an exit opening in said wall angularly disposed with respect to said entrance opening, a cylinder mounted in said casing for axial rotation therein, said cylinder having a passageway extending substantially diametrically therethrough adapted to register with said entrance and exit opening respectively upon rotation of the cylinder from a deposit receiving position to a deposit discharging position, means operative for locking the cylinder in the deposit discharging position, and means responsive to the presence of a deposit in said passageway for rendering said locking means inoperative.

30 9. In a depository of the class described, a substantially cylindrical casing having an entrance opening in the cylindrical wall thereof and an exit opening in said wall angularly disposed with respect to said entrance opening, a cylinder mounted in said casing for axial rotation therein, said cylinder having a passageway extending substan-

substantially diametrically therethrough adapted to register with said entrance and exit opening respectively upon rotation of the cylinder from a deposit receiving position to a deposit discharging position, means operative for locking the cylinder in the deposit discharging position and means including a movable plate member in said passageway and responsive to pressure of a deposit thereon for rendering the locking means inoperative.

10. In a depository of the class described, a substantially cylindrical casing having an entrance opening in the cylindrical wall thereof and an exit opening in said wall angularly disposed with respect to said entrance opening, a cylinder mounted in said casing for axial rotation therein, said cylinder having a passageway extending substantially diametrically therethrough adapted to register with said entrance and exit opening respectively upon rotation of the cylinder from a deposit receiving position to a deposit discharging position, locking means including a bolt slideable in an end wall of the casing, said cylinder having a socket positioned in a corresponding end wall of the cylinder to receive said bolt when the cylinder is in a discharging position, a blocking member carried by the cylinder and movable to block and unblock the entrance to the socket, and means responsive to the presence of a deposit in said passageway for moving the blocking member to block said socket entrance.

11. In a depository of the class described, a substantially cylindrical casing having an entrance opening in the cylindrical wall thereof and an exit opening in said wall angularly disposed with respect to said entrance opening, a cylinder mounted in said casing for axial rotation therein, said cylinder having a passageway extending substantially diametrically therethrough adapted to register with said entrance and exit opening respectively upon rotation of the cylinder from a deposit receiving position to a deposit discharging position, locking means including a bolt slideable in an end wall of the casing, said cylinder having a socket positioned in a corresponding end wall of the cylinder to receive said

8
bolt when the cylinder is in a discharging position, a pivoted blocking member carried by the cylinder and movable to block and unblock the entrance to said socket, resilient means normally urging the blocking member to an unblocking position, a depressible plate member in the passageway adapted to be depressed by a deposit therein, and means operatively connecting said plate member and blocking member whereby the blocking member blocks said socket entrance to prevent entrance of the bolt thereinto while a deposit is in said passageway.

12. In a depository of the class described, a substantially cylindrical casing having an entrance opening in the cylindrical wall thereof and an exit opening in said wall angularly disposed with respect to said entrance opening, a cylinder mounted in said casing for axial rotation therein, said cylinder having a passageway extending substantially diametrically therethrough adapted to register with said entrance and exit opening respectively upon rotation of the cylinder from a deposit receiving position to a deposit discharging position, means operative for locking the cylinder in the deposit discharging position, and means responsive to the presence of a deposit in said passageway for rendering said locking means inoperative, a hinged door member adapted to open and close said entrance opening, and means including a link having pivotal connections with said door and cylinder and arranged with respect thereto whereby opening movement of said door moves the cylinder to deposit receiving position and closing movement of said door moves said cylinder to deposit discharging position.
